UNITED STATES PATENT OFFICE

ROLAND CRAIG RUMBAUGH, OF SHREVEPORT, LOUISIANA

JACK POST

Application filed September 12, 1927. Serial No. 219,061.

My invention relates to jack posts which are used for supporting the power shaft in a walking beam pumping outfit, although of course, not limited to this particular use.

Briefly stated, the primary object of the invention is to provide a very simple, light, strong and efficient jack post of metal to take the place of the usual wooden jack post the component parts of wooden posts, such as are commonly used, being hard to obtain, a standard wooden post being incapable of standing the rigorous service to which the post is subjected and which hard usage will have no effect upon a post constructed with metal in accordance with my invention.

A more specific object of the invention is to provide a post having novel means for securing the shaft bearing in place thereon, which means also serves to reinforce the post to provide a more rigid structure.

The foregoing and other objects of the invention,—as will be more apparent hereinafter,—are attained by means of a novel combination and arrangement of parts to be hereinafter described and claimed,—reference being had to the accompanying drawings which illustrates the now preferred form of the invention. It is to be understood, however, that the invention is capable of other mechanical expressions within the scope of the subject matter claimed.

Referring specifically to the drawings, wherein the same reference characters have been used to designate the same parts in all views,

Figure 1 is a side elevation of a jack post constructed in accordance with my invention and illustrating the power wheel, crank shaft and pitman, which is adapted to oscillate the walking beam;

Figure 2 is a vertical sectional view taken on the line 2—2 of Figure 3;

Figure 3 is a fragmentary top plan view of the post;

Figure 4 is a section on the line 4—4 of Figure 1;

Figure 5 is a detailed perspective view of the pivot pin, and

Figure 6 is a detailed perspective of a bolt attaching device.

Referring specifically to the drawings, 1 designates a concrete or other sleeper,—of which there are two, one being disposed at either side of the crank shaft 2 and in spaced parallelism.

There are two jack posts 3, one being mounted on each of the sleepers 1. For purposes of description but one jack post will be referred to inasmuch as they are identical.

The jack post 3 comprises a U-shaped upstanding member 3^a the lower ends of which are suitably bolted against the inner faces of spaced angle beams 4, which are bolted to the sleeper 1, as indicated at 5.

Diagonal braces 6 are riveted to the inner sides of the upstanding post member 3^a adjacent the bight portion thereof and have their outer ends secured to the angle bars 4 by means of bolts 8. There are four reinforcing bars or prop members 6, Figure 4 illustrating two extending in opposite directions from each leg of the upstanding member 3^a. The lower ends of the prop members 6 are held in flat contact with the upstanding portions of the angle bars 4 by means of the outer sides of a clevis 9 which is pivoted up on the bolt 8.

Each of the prop members 6 is provided intermediate its ends with an auxiliary prop member 10 which is riveted thereto as at 11 and has its outer end riveted to the inner surface of the adjacent leg of upstanding member 3^a, as indicated at 12. Rivets or fastening means 12 may also secure member 3^a to angle beams 4.

The bearing which supports the crank shaft 2 comprises a saddle 13 having a rectangular groove or recess 14 in its bottom to receive the bight portion of the upstanding post member 3^a. The upper bearing member or cap 15 is provided with a recess 15^a into which the boss 13^a of the saddle member 13 is adapted to fit. The bearing members 13, 15 may be secured together by means of bolts 16 the heads of which are received in countersunk recesses in the bottom recess 14.

In order to removably secure the bearings 13, 15 in place upon the bight portion of the upstanding post member 3^a I provide turn-buckle rods 17 the lower ends of which are

engaged with the clevises 9 while the eyes 17^a at their upper ends are engaged in surface recesses at the rear portion of lugs 18 which are provided at either end of the 5 saddle member 13. The cap member 15 of the bearing is cored out at its upper surface adjacent each end as indicated at 19 so as to permit the eye 17^a of the turnbuckle rod 17 to be located in place, as shown in Figure 10 2 in the recess rearwardly of the outwardly projecting ear 18.

In order to make sure that the eyes 17^a do not become disengaged from the lugs 18, I 15 provide rods 20 extending through ears 18 and also through the holes in the superposed portion of the cap plate 16. While these rods 20 are not absolutely necessary, yet their use is preferable. The rods 20 in addition to serving as a means for securing the eyes 17^a 20 against disengagement from the lugs 18 also serve to rigidify the construction inasmuch as their lower ends are extended down through the sleeper 1 and have their terminal head portions engaged in the end slots or 25 bifurcations of keeper plates 21 which are positioned against the bottom space of the sleeper 1. As shown in Figure 2, there are two nuts on each of the rods 20 the nuts being designated at 22. One nut 22 bears against 30 the top face of a lug 18 while the other nut 22 bears against the top face of the cap 15.

From the foregoing description taken in connection with the accompanying drawings it will be readily appreciated by those skilled 35 in the art that I have constructed a very durable jack post involving a minimum number of parts.

When it is desired to remove the cap portion of the bearing 13, 15 this can be done by 40 merely taking off the nuts of the bolts 16 and removing the upper nuts 22 from the rods 20. As already explained the bolts 16 are not absolutely necessary and may be dispensed with where the rods 20 are employed.

45 Having thus described my invention, what I claim as new and desire to secure by Letters Patent is:—

1. A device of the class described comprising an upstanding U-shaped metal post, a base member having a pair of spaced upstanding flanges between which said post is disposed and to which the legs thereof are fastened, duplicate pairs of prop members fastened to the inner surfaces of the legs of said U-shaped post and extending diagonally downward in opposite directions, a bolt at either side of said post and extending through said base member flanges and the ends of each pair of prop members to anchor the latter, a bearing removably seated upon the upper bight portion end of said post, said bearing having ears at opposite sides, the upper surfaces of said ears having rear recesses, turnbuckle rods having ends engageable in said ear recesses, clevises carried by 50 55 60 65 70 75 80 85 90 10189 10190 10191 10192 10193 1019

securing the lower end of the respective brace members of each pair against the inner surface of the adjacent base flange, an auxiliary brace member secured to the inner surface of each of said aforementioned base members and intermediate the ends of the latter, the other ends of said auxiliary brace members being secured to the inner surface of the adjacent leg of said post and to the proximate base flange, and the lower ends of the auxiliary brace members at each side of the base being in substantial engagement and the other ends intersecting said first mentioned brace members at substantially a right angle.

5. The combination set forth in claim 4, and the securing means for the lower ends of said first mentioned brace members comprising a bolt extending through said flanges and each pair of brace members, a bearing upon said post, tie means secured to opposite ends of said bearing, a clevis upon each of said bolts and between the flanges and brace members, said clevis serving to hold the outer surfaces of said brace members 20 against said flanges, and said tie means being each secured to one of said clevises.

6. A device of the class described comprising an upstanding U-shaped metal post, a base member having a pair of spaced up- 30 standing flanges between which said post is disposed and to which the legs thereof are fastened, duplicate pairs of prop members fastened to the inner surfaces of the legs of said U-shaped post and extending diagonally 35 downward in opposite directions, a bolt at either side of said post and extending through said base member flanges and the ends of each pair of prop members to anchor the latter, a bearing block removably seated upon the upper bight portion end of said post, turnbuckle rods having ends engageable 40 with said bearing block, clevises carried by said bolts and carrying the other ends of said turnbuckle rods, the sides of said clevises engaging said prop members to hold the same 45 in engagement with the inner surfaces of said base member flanges, a cap member for said bearing, and post-stabilizing and reinforcing tie rods extending through said cap member 50 and bearing block to hold said cap member in place, and portions of said tie rods overlying block-engaged portions of said turnbuckle rods to prevent disengagement of 55 said turnbuckle rods from said bearing block, and means for anchoring said tie rods to said support.

7. A device of the class described comprising an upstanding U-shaped metal post, a base member having a pair of spaced up- 60 standing flanges between which said post is disposed and to which the legs thereof are fastened, duplicate pairs of prop members fastened to the inner surfaces of the legs of said U-shaped post and extending diagonally 65 downward in opposite directions, a bolt at

either side of said post and extending through said base member flanges and the ends of each pair of prop members to anchor the latter, a bearing block removably seated upon the upper bight portion end of said post, 70 turnbuckle rods having ends secured to said bearing block, clevises carried by said bolts and carrying the other ends of said turnbuckle rods, and the sides of said clevises engaging said prop members to hold the same 75 in engagement with the inner surfaces of said base member flanges.

In testimony whereof I affix my signature.

ROLAND CRAIG RUMBAUGH.
